3,170,526 DRILL BIT

Willie L. Chauvin, P.O. Box 206, Houma, La.
Filed Sept. 13, 1962, Ser. No. 223,325
4 Claims. (Cl. 175—270)

The present invention relates generally to drilling equipment and in particular to a drill bit for exploratory drilling.

An object of the present invention is to provide a drill bit which permits the user thereof to drill an exploratory hole, lower an explosive through a drill rod and through the bit to the bottom of the hole, withdraw the drill bit, and use the drill bit over and over again.

Another object of the present invention is to provide an exploratory drill bit which is inexpensive to manufacture, one which may be made in any size desirable, and one having means for partially disassembling of the bit at the bottom of a hole drilled by the bit.

A further object of the present invention is to provide an exploratory drill bit which is sturdy in construction, one simple in structure, and one which is highly effective in action.

These and other objects and advantages of the present invention will be fully apparent from the following description when taken in connection with the annexed drawing, in which:

FIGURE 1 is an elevational view of the drill bit of the present invention, a portion at the upper end being broken away.

FIGURE 2 is a view taken on the line 2—2 of FIGURE 1.

FIGURE 3 is a cross-sectional elevational view taken on the line 3—3 of FIGURE 2, and is a view in cross-section rotated 90° from the view shown in FIGURE 1.

Referring in detail to the drawing in which like numerals indicate like parts throughout the several views, in FIGURES 1 to 3, the reference numeral 10 designates an upright sleeve adapted to be secured to the lower end of a tubular drill rod or the like, the drill rod not being shown.

Depending from and exteriorly of the sleeve 10 are three teeth 12, 14, 16.

Associated with and spaced from the tooth 14 is an upright bar 18 parallel to the tooth 14 and forming with the tooth 14 a slot 20 defining a keeper for a bridge element 22 normally extending diametrically across the lower end of the sleeve 10 and having one end hingedly connected to the sleeve 10 for swinging movement from the normal position to an upright position below the sleeve 10, the swinging movement being shown in dotted lines in FIGURE 3.

The means connecting the bridge element 22 to the sleeve 10 for swinging movement consists in a bar 24 and tooth 26 arranged vertically with respect to the sleeve 10 and on the outside of the sleeve 10 diametrically opposite the tooth 14 and bar 18.

The bar 24 and tooth 26 are provided with aligned holes 28 and 30, respectively, as shown in FIGURE 2, and a bolt 32 has its shank extending through the holes 28 and 30 and through a hole 34 provided in the bridge element 22.

Means is provided for releasably holding the bridge element 22 in the bridging position. This means consists in a soft iron wire 36 extending through holes 38, 40, and 42 in the tooth 14, the bridge element 22, and the bar 18, respectively, as shown in FIGURE 2 in dotted lines.

The wire 36 is twisted upon itself to form a knot 44 after it has been inserted through the tooth 14, the bridge element 22, and the bar 18.

Depending from the central portion of the bridge

2

element 22 are a pair of teeth 46 and 48, one on each side of the element 22, and staggered with respect to each other.

A nut 50 having a cotter pin 52 therethrough, secures the bolt 32 in its position supporting the one end of the bridge element 22 on the sleeve 10.

In construction and use, the tooth 14 and the bar 18 constitute slot-forming support members for receiving the bridge element 22, and the bar 24 and tooth 26 constitute slot-forming holding members when the wire 36 is applied.

The drill bit of the present invention is attached to the lower end of a drill rod and the drill rod is reciprocated and rotated in the conventional manner drilling a hole with the teeth of the drill bit, suitable flushing material being pumped into the sleeve 10 and removed therefrom as is standard practice in drilling an exploratory hole.

When the hole is completed, it is only necessary to drop a heavy weight or tool into the sleeve 10 to break the wire 36 and permit the swinging movement of the bridge element 22 from its normal bridging position to a position out of the way and below the sleeve 10 so that the user of the drill bit may lower an explosive charge down the hole and through the sleeve 10 to the bottom of the hole, permitting the withdrawing of the sleeve 10 and its attached teeth for re-use in another hole.

Additional embodiments of the invention in this specification will occur to others and therefore it is intended that the scope of the invention be limited only by the appended claims and not by the embodiment described hereinabove. Accordingly, reference should be made to the following claims in determining the full scope of the invention.

What is claimed is:

35. 1. In a drill bit including an upright sleeve for attachment to a tubular drill rod, and at least one tooth and bar each projecting below the lower end of said sleeve spatially of each other and each disposed substantially exteriorly of said sleeve and in substantially parallel relation to each other, a bridge element normally extending diametrically across the lower end of said sleeve and having one end thereof hingedly connected between the tooth and the bar on said sleeve for swinging movement from the normal position to a generally vertical position below said sleeve, another tooth and bar spatially disposed to each other and projecting below the lower end of the sleeve diametrically opposite said one tooth and bar, at least one tooth carried by said bridge element for eliminating any core being formed by the tooth on the sleeve, and rupturable means operatively connected to the tooth and the bar on said sleeve for releasably holding the other end of said bridge element in the normal position in the space between the other tooth and bar.

45. 2. In a drill bit including an upright sleeve for attachment to a tubular drill rod, and a pair of teeth and bars each diametrically disposed about and projecting below the lower end of said sleeve and disposed sub-

50. stantially exteriorly of said sleeve and forming support members, a bridge element normally extending diametrically across the lower end of said sleeve and having one end thereof hingedly connected to one of said support members by a bolt for providing swinging movement from the normal position to a generally vertical position below said sleeve, at least one tooth carried by said bridge element centrally thereof for eliminating any core from being formed in the sleeve, and rupturable means operatively connected to the tooth and the bar of said sleeve releasably holding the free end of said bridge element in the normal position.

60. 3. In a drill bit including a cylindrical upright sleeve

70. 70. 3. In a drill bit including a cylindrical upright sleeve

for attachment to tubular drill rod, and a tooth and bar each projecting below the lower end of said sleeve and at each side of the sleeve and disposed substantially exteriorly of said sleeve at diametrically opposite positions thereof and forming support members, a bridge element normally extending diametrically across the lower end of said sleeve and having one end thereof hingedly connected from one of said support members for swinging movement from the normal position to a generally upright position below said sleeve, at least one tooth carried by said bridge element centrally thereof for eliminating any core being formed in said sleeve, the other of the support members carried by said sleeve for receiving said bridge element, and rupturable means releasably securing the other end of said bridge element to said other of the support members.

4. In a drill bit including an upright sleeve for attachment to a tubular drill rod, and a tooth and bar each projecting below the lower end of said sleeve and each disposed at substantially diametrical points of said sleeve

5 forming support members having a slot, a bridge element normally extending diametrically across the lower end of said sleeve and having one end thereof hingedly connected from one of said support members for swinging movement from the normal position to a generally upright position below said sleeve, at least one tooth carried by said bridge element centrally thereof, and rupturable means embodying a soft iron wire releasably securing the other end of said bridge element to the other 10 of the support members.
